US0D1038407S

(12) **United States Design Patent** (10) **Patent No.:** **US D1,038,407 S**
(45) **Date of Patent:** ** Aug. 6, 2024

(54) **HEARING AID**

(71) Applicants: **Anhui Huami Health Technology Co., Ltd.**, Hefei (CN); **Zepp, Inc.**, Cupertino, CA (US)

(72) Inventors: **Li Huang**, Hefei (CN); **Wei Zheng**, Hefei (CN)

(73) Assignees: **Zepp, Inc.**, Cupertino, CA (US); **Anhui Huami Health Technology Co., Ltd.**, Anhui FTZ (CN)

(**) Term: **15 Years**

(21) Appl. No.: **35/516,761**

(22) Filed: **Mar. 28, 2022**

(80) **Hague Agreement Data**

Int. Filing Date: **Mar. 28, 2022**

Int. Reg. No.: **DM/221317**

Int. Reg. Date: **Mar. 28, 2022**

Int. Reg. Pub. Date: **Mar. 31, 2023**

(30) **Foreign Application Priority Data**

Mar. 11, 2022 (CN) 202230126437.5

(51) **LOC (14) Cl.** 24-99

(52) **U.S. Cl.**

USPC **D24/174**

(57) **CLAIM**

The ornamental design for a hearing aid, as shown and described.

DESCRIPTION

- 3. Hearing aid
  - 4. Hearing aid
  - 3.1 : Perspective
  - 3.2 : Perspective
  - 3.3 : Front
  - 3.4 : Back
  - 3.5 : Left
  - 3.6 : Right
  - 3.7 : Top
  - 3.8 : Bottom
  - 4.1: Perspective
  - 4.2: Perspective
  - 4.3: Front
  - 4.4: Back
  - 4.5: Left
  - 4.6: Right
  - 4.7: Top
  - 4.8: Bottom
- 3.1) perspective view; 3.2) perspective view; 3.3) front view; 3.4) back view; 3.5) left view; 3.6) right view; 3.7) top view; 3.8) bottom view

(Continued)

view; **3.8**) bottom view; **4.1**) perspective view; **4.2**) perspective view; **4.3**) front view; **4.4**) back view; **4.5**) left view; **4.6**) right view; **4.7**) top view; **4.8**) bottom view; the shade lines in the figures show contour, not surface ornamentation and form no part of the claimed designs.

1 Claim, 16 Drawing Sheets
